UNITED STATES PATENT OFFICE.

FREDERICK SMITH, OF LONDON, ONTARIO, CANADA.

LUGGAGE-CARRIER FOR AUTOMOBILES.

1,357,736.

Specification of Letters Patent.

Patented Nov. 2, 1920.

Application filed May 1, 1920. Serial No. 378,258.

To all whom it may concern:

Be it known that I, FREDERICK SMITH, of the city of London, in the county of Middlesex and Province of Ontario, Dominion 5 of Canada, have invented a certain new and useful Improvement in Luggage-Carriers for Automobiles; and I hereby declare that the following is a full, clear, and exact description of the same.

10 This invention relates to a luggage carrier for automobiles which consists essentially of a horizontal member adapted to lie on the tread surface of the running board, and in its operative position to extend transversely across it, a vertical member separable from, and extending through, the horizontal member for detachably connecting these parts to the running board, and a flexible member attachable to the vertical and horizontal members.

15 The horizontal member may take the form of a flat or substantially flat bar apertured at one end to receive the vertical member and at the other end for the attachment of the flexible member.

20 The vertical member may take the form of a bolt to be inserted through the running board or to be inserted in a stationary nut therein, in the former case the bolt being provided with wing nuts arranged on opposite sides of the running board to clamp the vertical member thereto. The upper end of the vertical member is apertured for the attachment of the flexible member which may consist of a leather strap, webbing or the like.

25 For an understanding of the invention reference is to be had to the following description and accompanying drawings, in which:

30 Figure 1, is a perspective view of a running board showing the luggage carrier in position.

35 Fig. 2, is a plan view of the horizontal member,

Fig. 3, is an elevational view of the vertical member, and

40 Fig. 4, is a sectional view of a running board showing a stationary nut for holding the vertical member of the luggage carrier parts.

45 Like characters of reference refer to like

parts throughout the specification and drawings.

50 *a* represents the usual type of running board for an automobile in which is formed two apertures *a'* adjacent to its inner edge. *b* represents the horizontal member of the luggage carrier, this member in its operative position being adapted to lie transversely across the running board.

55 At one end of the horizontal member *b*, is an aperture *b'*, corresponding with its respective aperture *a'* in the running board, and at the other end of the horizontal member is an aperture *b''*. Between the apertures *b'*, *b''*, are a series of apertures *b³* arranged in a row lengthwise of the horizontal member for the purpose hereinafter described.

60 *c* represents the vertical member, which is of a height suitable to that of the luggage to be carried. The lower end *c'* of the vertical member is screw-threaded and corresponds in diameter with that of the apertures *a'*, *b'*, and the upper end is apertured as shown at *c''*.

65 As shown in Fig. 3, the vertical member is provided with two wing nuts *d*, *d'*, arranged on opposite sides of the running board *a*, to clamp the vertical member in position when the parts are assembled.

70 In the assembly of the parts the horizontal member in its operative position is arranged transversely of the running board with the aperture *b'* overlying the aperture *a'*. The screw threaded end *c'* of the vertical member is inserted through the apertures *b'*, *a'*, and clamped in position by the wing nuts *d*, *d'*, this clamping arrangement 75 securely locking both the vertical and horizontal members against displacement.

77 The luggage is placed to bear on the horizontal members and against the vertical members and is securely held in this position by the flexible member *e*, which in this case consists of a strap provided with snap hooks *h* to engage in the apertures *b''*, *c''*, of the horizontal and vertical members respectively, and with a take up such as a buckle *g* or the like interjacent its ends for contracting it against luggage upon the carrier. For large sized articles the snap hooks of the flexible members are engaged.

in the apertures b'' , c'' , but for small sized articles one of the snap hooks can engage any one of the intermediate apertures b^s of the horizontal member.

5 For suitcases, traveling bags and the like, it may not be necessary to extend the horizontal members beyond the edge of the running board, but for trunks and large sized articles it may be necessary to do so. In 10 both cases, however, the general principle of the parts is the same.

In Fig. 3, the vertical member is shown to be provided with wing nuts, but one of these nuts may be dispensed with and a 15 stationary nut f may be permanently inserted in the running board for each vertical member, as shown in Fig. 4.

Having thus fully described my invention, what I claim as new and desire to 20 secure by Letters Patent is:

25 1. A luggage carrier comprising a horizontal member adapted to lie transversely across the running board of an automobile having each end apertured, a vertical member, the lower end of which is screwthreaded and adapted to pass through the aperture at the inner end of the horizontal member and through the running board for the at-

tachment of the luggage carrier thereto, an aperture at the upper end of the vertical 30 member, and a flexible member detachably secured to the upper end of the vertical member and to the outer end of the horizontal member.

2. In a luggage carrier the combination 35 of a running board, having an aperture near its inner edge, a horizontal member adapted to lie transversely across the running board having at its inner end an aperture corresponding to the aperture through 40 the running board, a vertical member having its lower portion screwthreaded and adapted to pass through the aperture at the inner end of the horizontal member and the aperture in the running board, clamping 45 nuts for said screwthreaded portion to lock the vertical and horizontal members to the running board, and a flexible member attached to the upper end of the vertical member and to the outer end of the horizontal member.

Toronto, Ontario, April 22nd, 1920.

FREDERICK SMITH.
